DISPLAY PACKAGES

Jerry B. Giesler, Lombard, Ill., assignor to Waldorf Paper Products Company, St. Paul, Minn., a corporation of Minnesota

Filed Aug. 5, 1965, Ser. No. 477,421

2 Claims. (Cl. 206—78)

This invention relates to an improvement in display packages and deals particularly with a package in which an object is displayed through a film of transparent material in a window opening of the package and which may be easily opened to remove the object.

At the present time, many objects are displayed through windows in one or both of a pair of paperboard panels having a transparent film extending across the window opening, the marginal edges of which are sandwiched between the panels. One of the biggest objections to packages of this type lies in the fact that they are notoriously difficult to open. The plastic film which overlies the object is tough and somewhat pliable, and the panels are usually heat sealed together so they are very difficult to tear apart. As a result, it is usually necessary to cut through the plastic film in order to remove the object contained. This requires the use of a knife or a similar instrument which is not always readily available.

It is an object of the present invention to provide a display package of the general type described including two panels, which are preferably foldably connected along one edge and which may be folded into substantially superimposed relation. Either one or both of the panels is provided with a window opening which is slightly greater in size than the outline size of the object to be contained. A film which is preferably a transparent plastic film of heat shrinkable material is secured to the apertured panel or panels to overlie the window opening, the film being secured to the inner surface of the panel or panels so as to be between the panels when they are folded together. When the panels are folded together, with the object therebetween, the film stretches to enclose the object.

In preferred form, one or both of the panels includes a transverse score line extending parallel to the folded edges of the panels, and preferably intersecting the window aperture. The areas of the panels between the score line or lines and the folded edges of the panels are securely sealed together. On the other hand, the areas of the panels which are between the score line and the edges of the panels opposite the folded edges are sealed together only in relatively small areas which may be separated with comparative ease. As a result, when these ends of the panels which are between the score line and the edges readily fracture in the small areas of connection permitting the enclosed object or objects to be easily removed.

A further feature of the present invention resides in the provision of a simple and effective means of grasping the panels so that they may be separated by fracturing the relatively small areas of attachment. Each of the panels is provided with an ear which projects beyond the periphery of the other panels, each ear being readily engageable between the thumb and forefinger of a hand. Preferably, the ears project from the end of the panels most remote from the folded edge so that the panels may be torn apart at this end.

A feature of the present invention resides in the provision of a structure which, in its preferred form, comprises a pair of hingedly connected panels containing registrable window openings, and a film of heat sealable material which is adhered to the flat blank in order to extend over both of the window openings. The edges of the film are marginally adhered to the inner surfaces of

2

the two panels. When the panels are swung together to enclose the object, the surfaces of the film are brought into contact. The folded panels may then be sealed by applying heat and pressure to the areas of the panels between the score line and the folded edges of the panels and by applying heat and pressure to small spaced areas between the score line and the free ends of the panels. Thus the sealing of the panels may be accomplished in one operation. Heat may then be applied to the film to shrink the film about the object if it is so desired.

In the following description, the word "object" has been used to describe the contents of the package, as display packages of this type are most commonly used to display a single object. However, it should be understood that a plurality of parts may comprise the "object" rather than a single piece.

These and other objects and novel features of the present invention will be more clearly and fully set forth in the following specification and claims.

20 In the drawings forming a part of the specification:

FIGURE 1 is a perspective view of the display package in closed position.

FIGURE 2 is a perspective view of the display package after it has been opened to remove the object contained.

25 FIGURE 3 is a plan view of the blank, showing in dotted outline, the areas in which the panel portions are secured together.

FIGURE 4 is a diagrammatic view of the paperboard blank showing in general the areas of adhesive for connecting the transparent film to the blank.

FIGURE 5 is a view similar to FIGURE 4 showing the film adhered to the blank.

FIGURE 6 is a diagrammatic view showing a modified form of blank.

35 FIGURE 7 is a diagrammatic view of the paperboard blank showing in general the areas of adhesive for connecting the transparent film to the blank.

FIGURE 8 is a diagrammatic view showing the blank in its completed form.

40 FIGURE 9 is a plan view of the blank, showing in dotted outline, the areas in which the panel portions are secured together.

FIGURE 10 is a diagrammatic view of the paperboard blank showing in general the areas of adhesive for connecting the transparent film to the blank.

45 FIGURE 11 is a diagrammatic view of the paperboard blank showing in general the areas of adhesive for connecting the transparent film to the blank.

FIGURE 12 is a diagrammatic view of the paperboard blank showing in general the areas of adhesive for connecting the transparent film to the blank.

50 FIGURE 13 is a diagrammatic view of the paperboard blank showing in general the areas of adhesive for connecting the transparent film to the blank.

FIGURE 14 is a diagrammatic view of the paperboard blank showing in general the areas of adhesive for connecting the transparent film to the blank.

55 FIGURE 15 is a diagrammatic view of the paperboard blank showing in general the areas of adhesive for connecting the transparent film to the blank.

FIGURE 16 is a diagrammatic view of the paperboard blank showing in general the areas of adhesive for connecting the transparent film to the blank.

60 FIGURE 17 is a diagrammatic view of the paperboard blank showing in general the areas of adhesive for connecting the transparent film to the blank.

FIGURE 18 is a diagrammatic view of the paperboard blank showing in general the areas of adhesive for connecting the transparent film to the blank.

65 FIGURE 19 is a diagrammatic view of the paperboard blank showing in general the areas of adhesive for connecting the transparent film to the blank.

70 FIGURE 20 is a diagrammatic view of the paperboard blank showing in general the areas of adhesive for connecting the transparent film to the blank.

shown as including a pair of elongated rectangular windows 23 and 24 which are of larger dimensions than the outline shape of the object B. As a result, a portion of the object may project through the windows enclosed within the plastic film.

The film 21 is preferably transparent, and is preferably a material which will shrink when subjected to heat. The material may be a film such as polyvinyl chloride, polyethylene, or polypropylene. The film is sufficiently elastic to extend about the object when the panels are folded together and will shrink snugly about the object when the film is heated. The adhesive 22 extends entirely about the apertures 23 and 24.

A fold line 25 extends across the panel 14 parallel to the fold line 11, and preferably intersecting the window 23. A similar fold line 26 extends across the panel 15 parallel to the fold line 11 and spaced therefrom a distance equal to the distance between the fold lines 11 and 25. As a result, the fold lines 25 and 26 register when the package is closed. The package will operate effectively even if one of the fold lines 25 or 26 are omitted, but the object is more readily accessible after the package is opened if both fold lines are present.

The operation of the package is believed obvious from the foregoing description. The object may be placed overlying the window 24 in the panel 15, the window preferably overlying a pocket shaped similarly to the window. The panel 14 is folded to overlie the object, the film stretching so that portions of the object extend through both windows. If necessary, the resiliency of the film may be increased by heating during this process.

When the panels are folded into superimposed relation, as indicated in FIGURE 3 of the drawings, heat and pressure are applied to seal marginal portions of the films in face contact. As is indicated in FIGURE 3, solid heating bars may be applied to the shaded areas 28 between the score lines 25, 26 and the folded edges of the panels along the fold line 11. However, in the area of the panels between the score lines 25, 26 and the free ends of the panels 14 and 15, only small spaced areas of heat and pressure are applied. This is accomplished by providing the heating die with a series of flat ended projections which engage the panels, the remainder of the heating die being held in spaced relation to the panels. As a result, the areas of the panels outwardly of the score lines are secured together with a connection which may be fractured with comparative ease.

When it is desired to open the package A, the ear 16 is grasped between the thumb and forefinger of one hand and the ear 19 is grasped between the thumb and finger of the other hand. The ears 16 and 19 are then pulled apart, hingeing the outer portions of the panels along the score lines 25 and 26, and rupturing the areas of connection which are indicated by the numeral 27. When the outer ends of the panels are spread apart, as indicated in FIGURE 2 of the drawings, the object B may be readily removed.

In structures where the object is not of excessive thickness, one of the panels may be solid and only the other of the panels may be apertured. Such an arrangement is indicated in FIGURE 6 of the drawings where a blank 29 is indicated which is generally similar to the blank 10. The blank 29 is centrally folded at 30 to provide a pair of panels 31 and 32 which may be identical in shape to the panels 14 and 15. Only the panel 31 is provided with a window opening 33, the panel 32 being imperforate. A rectangular sheet of film 34 is marginally

5 attached to the panel 31 to overlie the window 33. The panels 31 and 32 are provided with score lines 35 and 36 which will register when the blank is folded. If desired, the score line 36 may be omitted as the object B will be completely on the surface of the panel 32 when the package is opened.

The blank C is closed in the manner which has been previously described, the object B extending almost entirely through the window 33. The two panels are sealed in the manner previously described, the areas of the panels between the central fold line 30 and the score lines 35 and 36 usually being sealed over substantial areas while the portions of the panels outwardly of these score lines are attached only in relatively small areas. In this arrangement, the film 34 must be capable of heat sealing to the panel 32, or the panel 32 must be coated with heat sealable film. Alternatively, the transparent film 34 may be secured overlying the panel 32 so that the surfaces of the film may be heat sealed together over the desired areas.

10 In accordance with the patent statutes, I have described the principles of construction and operation of my improvement in display packages; while I have endeavored to set forth the best embodiment thereof, I desire to have it understood that obvious changes may be made within the scope of the following claims without departing from the spirit of my invention.

15 The claims:

1. A display package including:
  - (a) a pair of elongated paperboard panels in substantially superimposed relation,
  - (b) a score line extending across each of said panels parallel to the ends of said panels,
  - (c) said score lines being in registered relation,
  - (d) at least one of said panels having a window opening therein,
  - (e) one said score line intersecting said window opening,
  - (f) a transparent film secured to said one panel extending across said window opening,
  - (g) means securing said panels along areas of attachment with said film sandwiched between said panels,
  - (h) an object having an outline size smaller than said window enclosed on at least one side by said film extending through said window,
  - (i) each said panel including an ear projecting beyond the periphery of the other said panel whereby said ears may be grasped to pull said panels apart and
  - (j) the portions of said panels and film adjoining the edges of said panels intermediate said score lines and said ears being spacedly secured together in areas which are small relative to the area of contact.
2. The structure of claim 1 and in which said panels have registered window openings therethrough.
